UNITED STATES PATENT OFFICE.

EDWIN J. SHRADER, OF SALT LAKE CITY, UTAH TERRITORY, ASSIGNOR OF
ONE-HALF TO CHARLES F. KARNS, OF SAME PLACE.

TRACTION-ENGINE.

SPECIFICATION forming part of Letters Patent No. 548,470, dated October 22, 1895.

Application filed August 7, 1895. Serial No. 558,548. (No model.)

To all whom it may concern:

Be it known that I, EDWIN J. SHRADER, a citizen of the United States, residing at Salt Lake City, in the county of Salt Lake, Utah 5 Territory, have invented certain new and useful Improvements in Traction-Engines; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 This invention relates to improvements in traction-engines; and it consists in placing a shaft driven by steam-engines or otherwise a suitable distance above the ground and transmitting the power therefrom to the driving-wheels by means of coupling-rods connected 20 from the disks or cranks at each end of the shaft to suitable pins on the driving-wheels, the said driving-wheels resting in direct contact with the inner faces of the rims of auxiliary drive-wheels or revolving tracks, as 25 will be hereinafter more fully described.

The object of the invention is to first apply 30 the power from the cylinders to a disk upon the engine-shaft and thence transmit the power to the driving-wheels by means of a connecting-rod between the said disk and the driving-wheels, instead of having the disk serve as a driving-wheel, and as such in direct contact with the rim of the auxiliary 35 driver or endless track and out of direct line of the cylinders.

The invention is clearly illustrated in the accompanying drawings, in which—

Figure 1 is a side elevation of a traction-engine with my invention applied thereto, the front edge of the auxiliary driving-wheel or endless track being removed. Fig. 2 is a plan view of the operating mechanism, the endless track or driving-wheel being in horizontal section, with the journal-bearing of the 45 endless track removed. Fig. 3 is a vertical section taken through the trunnion and bolster-frame.

A represents the boiler of a traction-engine, 50 which has the trunnion B rigidly secured to its rear end, and which trunnion fits in a

socket C made to receive it upon the bolster-frame D. In the under side of the trunnion B and in the bottom of the socket C are provided suitable grooves, and within these 55 grooves between the trunnion and its socket are placed suitable balls, rollers, or other anti-friction devices G, of any kind which will serve to decrease the friction between the parts.

Passing through the trunnion B and the bolster-frame D is the king-bolt H, which has a spring I of any suitable form applied to its lower end, and which spring serves to hold the trunnion in its socket, but at the same 60 time allows it to yield under any undue strain. This trunnion, socket, and king-bolt enable the driving portions of the engine to be turned sufficiently to permit the engine to be guided in its backward movements. The 65 outer ends of the bolster-frame D are turned upward, and projecting from these upturned ends are pivoted or sleeved the centers L of the auxiliary driving-wheels or revolving tracks X, which are provided with flanges N 70 upon their edges. These auxiliary driving-wheels or endless tracks are provided with spokes X', which spokes connect the flanges N upon the outer edge of the endless track 75 with the hub, as shown in Fig. 3 of the drawings.

The horizontal frame O is secured to the under side of the bolster-frame D and is supported by the springs Q, mounted upon the frame, and upon the forward ends of the frame 85 O are placed the cylinders P, from which motion is transmitted to the shaft S. This shaft S is raised a considerable distance above the ground and is provided with a disk S', which disk is connected with the driving-wheel V by 90 a coupling-rod U. The said shaft S is placed in direct line with the cylinder P, so as to receive the power direct and with as little loss from friction or other cause as possible.

The driving-wheel V is in direct contact 95 with the smooth inner surface of the rim of the auxiliary driving-wheel or revolving track X, and said wheel V carries the weight of the machine. This wheel V is here shown as larger than the disks S' on the engine-shaft; 100 but I do not limit myself in this respect, for it is evident that the size of the said disks may,

if desired, be larger than the driving-wheel. The driving-surface of the wheel V being perfectly smooth and the inner surface of the track being also smooth, springs to support 5 the boiler can be used. Were these parts toothed springs could not be used advantageously.

The tension between the driving-wheel V and the auxiliary wheels or endless tracks X 10 is regulated by means of set-screws Y or their equivalents, so that the contact can never become sufficiently great to make the wheel V act as a brake upon the tracks or impede its motion in any manner.

15 As herein shown, the axle W is mounted in suitable boxes applied to the under side of the frame O, which is provided with pedestals to retain the boxes in position.

Having thus described my invention, what 20 I claim to be new, and desire to secure by Letters Patent, is—

1. In a traction engine, steam cylinders, the engine shaft placed in line therewith, the

disks of said engine shaft, driving wheels, the rods connecting said disks and driving 25 wheels, and the revolving tracks or auxiliary driving wheels in direct contact with and driven by the driving wheels substantially as shown and described.

2. In a traction engine, the boiler, a supporting frame connected thereto, the driving cylinder mounted on the frame, the engine shaft in line with the cylinders, the disk thereon, the connecting rods U and driving wheels V operated by the rods, combined 30 with the auxiliary driving wheels or revolving tracks having their inner surfaces in direct contact with the outer surface of the driving wheel, substantially as described.

In testimony whereof I affix my signature 40 in presence of two witnesses.

EDWIN J. SHRADER.
